UNITED STATES PATENT OFFICE.

GEORGE M. ATWOOD, OF COLFAX, CALIFORNIA.

COMBINED STEP-LADDER AND IRONING-BOARD.

1,145,396.

Specification of Letters Patent.

Patented July 6, 1915.

Application filed January 14, 1914. Serial No. 812,143.

To all whom it may concern:

Be it known that I, GEORGE M. ATWOOD, a citizen of the United States, residing at Colfax, in the county of Placer, State of California, have invented certain new and useful Improvements in Combined Step-Ladders and Ironing-Boards; and I do hereby declare the following to be a full, clear, and exact description of the invention, such 10 as will enable others skilled in the art to which it appertains to make and use the same.

This invention relates to combination devices and more particularly to combined ironing boards and step ladders.

An object of the invention is to provide a device of this character of improved construction and which may be folded in compact form when not in use.

Another object is to generally improve and simplify the construction of devices of this character and increase the efficiency thereof.

With these and other objects in view, this invention resides in the novel features of construction, formations, combinations and arrangements of parts to be hereinafter more fully described, claimed and illustrated in the accompanying drawing, in 50 which:—

Figure 1 is an elevational view of the device in condition for use as an ironing board. Fig. 2 is a top plan view of the device. Fig. 3 is a vertical sectional view on line 3—3 of Fig. 1. Fig. 4 is an end view of the device. Fig. 5 is a front elevational view of the device in position for use as a step ladder. Fig. 6 is a side elevation at right angles to Fig. 5.

Referring more specifically to the drawing in which similar reference characters designate corresponding parts throughout, 10 designates the ironing board proper, to the under face of which is secured the central portion of the U-shaped member 11, adjacent the wide end of said board. The arms of the U-shaped member are pivoted between the side rails 12 of the ladder which is indicated by the numeral 13. The pivot pin 14 passes through the side rails 12 immediately beneath the upper step 15 and through the arms of the U-shaped member 11, as clearly shown in the drawing. The supporting legs 16 are also pivoted upon the 50 opposite ends of the pivot pin 14 and are suitably connected adjacent their opposite

ends by means of the connecting and bracing rod 17 which is substantially U-shaped to permit folding of the legs 16 against the outer faces of the side rails 12 when the 60 device is used as a step ladder or when the same is folded in compact form.

The supporting legs 16 are provided with suitable notches 18 in their upper faces and near the upper ends thereof to accommodate 65 the lower edge of the step 15, when the device is used as an ironing board. The opposite ends of the board 10 are pointed as shown at 20 and the ironing board supporting legs 21 have their upper ends secured to 70 the edges of the board at this point. The lower ends are beveled upon their inner faces and adapted for clamping engagement 75 against the outer faces of the side rails 12 at their lower flared portions as shown in Figs. 1 to 4 inclusive to support the ironing board 10 in a horizontal position. A U-shaped bracing and connecting member 22 has its opposite bent ends secured to the supporting legs 21 near the lower ends 80 thereof to properly connect and brace said legs and connect the same to be folded in alignment with the ironing board proper 10 when the device is folded in compact form, or when the device is used as a step 85 ladder. When the device is to be employed as a step ladder the connecting member 22 engages against the lower end of the ironing board proper, thus preventing the legs 21 from swinging upon their pivots. 90

It will be apparent that the pivoted movement of the U shaped member 11 upon the pivot pin 14 is limited by engagement of the upper end of the ironing board proper 10 with the edge of the upper step 15. 95

It will further be apparent that the side rails 12 are suitably connected as shown at 12 to prevent spreading of said rails.

From the foregoing it will be apparent that I have provided a combination ironing board and ladder of extremely simple construction and which will be highly efficient in use. 100

It will be evident that minor changes may be made within the scope of the appended 105 claims without in any way departing from the spirit of the invention.

What is claimed is:—

1. In a combined ironing board and step ladder, a ladder section comprising downwardly diverging side rails, cross bars connecting said rails and maintaining them in 110

- a predetermined position, a shaft extending between the upper ends of the side rails, legs pivotally mounted on the said shaft, an ironing board section pivotally mounted 5 on the said shaft, supporting legs pivotally mounted on the opposite sides of the ironing board section adjacent the free end thereof, and a rod connecting the said legs adjacent their lower ends, the said legs being constructed and arranged to straddle the side rails of the ladder section and bind against the outer faces of the said rails to support the ironing board section, the divergence of the said side rails preventing the downward 10 displacement of the said supporting legs.
2. In a combined step ladder and ironing board, a ladder section including spaced side rails and cross bars extending between and connected to the same, an ironing board 15 section pivoted to the upper end of the said side rails and being of lesser length than the said rails, and legs pivoted to the said ironing board section adjacent the free end thereof constructed and arranged to form 20 the supporting legs of the ladder section
- 25

and to support the ironing board section on the said ladder section.

3. A combined step ladder and ironing board, comprising a ladder section, an ironing board section pivoted to the upper end 30 of the said ladder section, legs pivotally mounted on the opposite sides of said ironing board section adjacent the free end thereof, a cross bar connected to the said legs adjacent their ends, the said cross bar 35 being constructed and arranged to engage the lower end of the ironing board section when the device is used as a ladder to maintain the said ironing board section and legs in alinement, and to engage the edges of 40 the side rails of the ladder section to maintain the legs in predetermined relation with respect to the said ladder section when the device is used as an ironing board.

In testimony whereof, I affix my signature, 45 in presence of two witnesses.

GEORGE M. ATWOOD.
